poration of Delaware

Application May 18, 1933, Serial No. 671,660

71 Claims. (CL 200—117)

My present invention relates to electric fuse devices and the instant application is a continuation in part of my copending application Serial No. 559,846, filed August 28, 1931.

5 While the specific embodiments which I shall illustrate are adapted for interrupting high tension current and for use in expulsion type fuses and cut-outs of the character shown in my copending application above identified, the invention is not to be limited to such specific application, nor is the invention to be limited to high voltage only.

10 In the fuse element and fuse element assemblies of fuse devices of the type with which my present invention is concerned, certain difficulties have been encountered. One difficulty has been in obtaining the desired original accuracy of the time current blowing characteristics and the matter of permanence of the time current blowing characteristics or, in other words, the maintenance of the desired original accuracy of the time current blowing characteristics over long periods of time has presented another difficulty.

15 One of the reasons for the difficulties heretofore encountered lies in the fact that the oxides of the fuse elements or fuse links previously employed are non-conducting or relatively non-conducting and, furthermore, flake off and thereby reduce or vary the cross-section of the element.

20 Another reason for the prior difficulties lies in the fact that the fuse element has been exposed to atmosphere, gases and moisture.

25 A still further reason for the difficulties previously encountered lies in the fact that the fuse element and fuse element assemblies have not had the desired rigidity between the parts connected thereby but have been relatively free for movement between such parts.

30 One of the objects of the present invention is to overcome these difficulties heretofore encountered.

35 Another and more specific object is to improve the original accuracy of the time current blowing characteristics of the fuse element and fuse element assembly.

40 Another object is to improve the permanence of the time current blowing characteristics of the fuse element and fuse element assembly, or, in other words, to maintain better the desired original accuracy of the time current blowing characteristics over long periods of time.

45 Another object is to construct the fuse element and fuse element assembly so that same may be used either in the Schweitzer and Conrad type spring actuated expulsion fuse or in ordinary air

expulsion fuses. This gives the element and element assembly a highly desirable universal character.

5 The fuse element which I employ is preferably formed of a material whose oxide is a conductor. It and the tensile or strain wire are both preferably completely enclosed and shielded from atmosphere, gases and moisture. And the fuse element assembly is held rigidly between the parts between which it is connected, the fuse element being held rigidly and against crimping, and it and the other parts of the fuse element assembly being held rigidly against movement relative to and between the parts connected thereby.

10 Another feature of the present invention consists in providing the fuse element assembly with a projecting tail part or extension which may be grasped conveniently for the purpose of setting the fuse and which, after the fuse is set, may be cut off or removed.

15 Another feature consists in providing a secondary enclosure which telescopes or slips off the element assembly. With this secondary enclosure in place and the element assembly connected to the spring system, the element assembly is ready for use with spring type expulsion fuses and, with the secondary enclosure slipped off or removed and the element assembly disconnected from the spring system, it is ready for use with ordinary air expulsion fuses.

20 I believe that I have or hereinafter shall state with certainty the difficulties heretofore encountered, the reasons therefor, as well as the features of the present invention and the manner in which the previous difficulties are overcome thereby, but I reserve the right to revise the same or propound different theories should I become aware of results or features of which I am not now aware so long as any revisions or any additional features or results are based upon the following detailed disclosure as to how my invention may be practiced and employed.

25 Further features and advantages and a concrete understanding of the present invention will be more apparent from the following detailed description taken in connection with the accompanying drawings, in which:

Figure 20 is a detail transverse section taken on the line 20—20 of Figure 18.

The fuse shown in Figure 1 comprises a casing 55 5 in the form of a cylindrical tube. This tube is preferably formed of "bakelite" with a hard insulating fiber liner known as "Conite" or as "Horn Fiber" which does not carbonize under heat, but it is to be understood that any other 60 suitable or preferred insulating material may be employed. A ferrule 6 of cast hard bronze or other suitable or preferred material fits over the upper end of the tube 5 and is rigidly secured thereto by means of a pair of screws 7 and 8.

65 These screws are threaded through diametrically opposite sides of the ferrule 6 and into the wall of the tube 5, the upper end of which may be reduced to seat the lower end of the ferrule at 8.

The upper end of the ferrule 6 has a pair of 70 laterally extending arms 10 (only one of which is shown) formed integral with the ferrule, and spaced below the arms 10 is a second pair of generally parallel arms 11 also formed integral with the ferrule. Extending diametrically oppositely from the arms 10 and 11 and integral with

the ferrule 6 is a hook 12 provided for the purpose of attachment of the upper end of the fuse to the cover of the cut-out box (not shown).

5 The details of the upper spring contact clip are more fully disclosed in my copending application herein identified and form no part of the present invention. Suffice it, therefore, to explain here that this clip comprises a plurality of laterally extending and generally parallel contact wires preferably of copper and preferably with inherent springiness, although this may vary. These contact wires are indicated at 13,

10 there being in the illustrated embodiment four of these wires in superposed relation on each side and between each arm 10 and the underlying arm 11.

15 The ferrule ends of the contact wires 13 are firmly and rigidly anchored in the ferrule and the outer ends of these wires 13 are looped at 15.

Pins 16, formed of brass rod or other suitable material, extend through these looped ends 15 and are anchored at their opposite ends in the arms 10 and 11.

20 The looped ends 15 are the contact ends and the pins 16 hold these ends in place and against undue displacement but, at the same time, fit sufficiently loosely in the looped ends 15 to permit freedom of operation and closing of these ends upon the contact lug (not shown) with which the upper spring contact clip cooperates.

25 Washers 17, on the pins 16 and between the respective looped ends 15 of the contact wires 13 and between the arms 10 and 11 and the uppermost and lowermost contact wires, provide spacers for spacing and maintaining the desired relative positioning of the looped ends of the contact wires.

30 The lower ferrule 18 of cast hard bronze or other suitable material is split at 19 and clamped by screws 20 upon the tubular casing 5. This ferrule 18 has arms and contact wires (not shown) corresponding with the arms and contact wires of the upper spring contact.

35 The lower end of the ferrule 18 is threaded internally at 22 to receive a cap screw 23. This cap screw 23 has a hexagonal head 24 to facilitate turning the same into and out of the upper end 40 of the ferrule 18. The cap screw 23 closes the top of the tube 5 and this cap screw has an integral axial boss 25 extending into the tube 5. The boss 25 has a helical groove 26 for receiving the upper end of the spring 27 by threaded engagement therewith.

45 The upper end of the ferrule 6 is threaded internally at 22 to receive a cap screw 23. This cap screw 23 has a hexagonal head 24 to facilitate turning the same into and out of the upper end 45 of the ferrule 6. The cap screw 23 closes the top of the tube 5 and this cap screw has an integral axial boss 25 extending into the tube 5. The boss 25 has a helical groove 26 for receiving the upper end of the spring 27 by threaded engagement therewith.

50 The boss 25 is reduced at its lower end and has a socket 29 in which one end of a flexible braided conductor 30 is rigidly secured. This braided conductor 30 is made of copper or the like and its opposite end is connected with the lower terminal member 32 by rigidly securing it in the socket 33. The lower terminal 32 has a helical groove formed therein for threaded engagement with the lower end of the spring 27 and the lower terminal is thus suspended by the spring. This lower terminal 32 has a flattened portion 35 to receive a stud 36 which may be secured in place by means of a pin 37. The fuse 55 element or fuse link 38 extends around the stud 36 and is bolted to the terminal 32 by means of a nut 39 threaded upon the stud 36.

55 The stud 40 is threaded throughout its length and is undercut at approximately its center, as indicated at 41. One end of the fuse link 38 is secured to the terminal 32 within the fuse casing 5 by means of the stud 36 and nut 39, as previously pointed out, and the terminal 32 is then drawn downwardly as by grasping the downwardly 60 projecting tail end of the link 38 and pulling

65 projecting tail end of the link 38 and pulling

70 projecting tail end of the link 38 and pulling

75 projecting tail end of the link 38 and pulling

the lower terminal 32 downwardly against the tension of spring 27. It is to be understood that the parts are so proportioned that the lower tail end of the link 38 will project down below the bottom of the fuse casing 5 when the spring 27 is retracted and the lower terminal 32 raised. Then, with the lower end of the spring 27 pulled down to extended position, the lower end of the link 38 is folded up around the lower end of the 10 casing 5 as shown, and the free end of the tail projection of the link 38 is secured to the stud 40 by means of a nut 42 threaded upon the extending end of the stud 40. A circuit is thus established from the terminal 32, through the 15 fuse link 38, to the lower ferrule 18, and with the parts set, as shown, the circuit is completed from the terminal 32, through the braided conductor 30, and possibly partially through the spring 27, to the upper ferrule 6, through the 20 boss 25 and the cap screw 23.

The fuse link 38 is made of suitable fusible material, preferably a fusible material whose oxide is a conductor as, for example, pure silver wire, and it has a portion 45 of reduced cross 25 sectional area at a point along its length within the tube 5, said reduced portion 45 being surrounded by a cork 46 disposed within the lower end of the tube 5. It is to be understood that the showing of the fuse link 38 in Figure 1 is 30 more or less diagrammatic. This element may be similar to the element shown in Nicholas J. Conrad Patent No. 1,818,382, dated August 11, 1931, or it may consist of a silver wire paralleled by a nickel chromium alloy strain wire. The 35 formation of the fuse link 38 of silver or some other material whose oxide is a conductor provides a fuse link which will not flake off, deteriorate, or become reduced in cross section. This enables making the time current blowing characteristics accurate originally and tends to maintain the desired original accuracy of the time current blowing characteristics over long periods of time. The enclosure of the reduced portion 45 of the fuse link seals the same from atmosphere, gases and moisture, and tends also 45 to maintain the desired original accuracy of the time current blowing characteristics, particularly along the active part of the fuse link.

When the fuse link blows, it blows at the reduced portion 45 and, the tension of the spring 27 being thereby released, the spring quickly snaps the terminal 32 upwardly and away from the point of blowing of the fuse to draw out quickly and extinguish any arc that may form.

55 The fuse element assembly shown in Figures 2, 3 and 4, comprises a short length of copper tubing 48 and a somewhat longer length of copper tubing 49 flattened and thereby secured upon the opposite ends of the closed loop strain element 60 or tensile wire 50 arranged to bear the mechanical strength and upon the opposite ends of the crimped fuse wire 51. The fuse wire 51 is made of suitable material, preferably a fusible material whose oxide is a conductor, such as pure silver, and the strain element 50 preferably is of "Chromel" A wire. The cork enclosure 52 surrounds the fuse element and strain wire assembly as shown, and this cork member 52 is made up of two half round corks having complementary depressions 53 and surrounded and held together by a water-proofed paper tube 54. The tube 54 may be of gummed paper or it may be a thin fiber tube, or of other suitable or preferred material. 70 The cork is compressed and the two halves se-

cured together by forcing them into and enclosing them in the tube 54.

The silver fuse element 51 is enclosed in thin sheet mica at 55 to prevent contact with the strain wire 50 and to keep heat from the fuse element from charring the cork. In this manner, I combine a fuse link 51 of silver or other material, whose oxide is a conductor, with a strain wire, and I completely enclose and shield both from atmosphere, gases and moisture.

10 It will be noted further that the opposite ends of the tightly compressed cork sections project lengthwise sufficiently to fit over and be compressed tightly upon the adjacent end of the copper tubing 49 and upon the copper tubing 48 at 15 the opposite end of the fuse element assembly. The forcing of the cork member 52 into the tube 54 binds the opposite ends of the cork firmly and rigidly to the copper terminals 48 and 49 of the 20 fuse element assembly, holding the terminals 48 and 49 of the fuse element assembly rigidly together, and the entire fuse assembly is a rigid unit so that the fuse element and strain wire will not have free movement between the parts connected thereby as heretofore. The flattened section of 25 copper tubing 49 has an eye 56 which may be secured to the lower inside and movable terminal 32 by means of a nut 58 threaded upon the extending end of the stud 36 as described in connection with the preceding embodiment, the eye 56 being 30 adapted to be passed over the stud 36.

The extension 57 of hot rolled copper or other suitable material has the tail end 61 which, when the spring 27 is retracted, extends down below the lower end of the fuse casing 5 so that it may be gripped conveniently for setting the fuse and placing the spring 27 under tension as described in connection with the preceding embodiment. As before, the fuse is set by grasping the tail extension 61 and pulling the same downwardly, and, with this tail end 61 of the extension 57 pulled downwardly and the spring 27 under tension, the extension 57 is folded up over the lower end of the fuse casing 5 and the opening 58 is placed over the stud 40 and secured to the stud 40 by means of the nut 42 threaded upon the extending end of the stud, as before. With the fuse thus set, and the end of the strip 57 with the opening 58 anchored to the lower fuse terminal by means of the stud 40, the circuit is completed from the terminal 18 through the strip 57, the fuse link and strain wire assembly, and the short length of copper tubing 49, to the terminal member 32. After the end of the strip 57, adjacent the opening 58, is secured to the stud 40, the tail end 61 of the extension may be removed by cutting or severing it at the dot and dash line 62 in Figure 2, suitable openings 59 being provided to facilitate the cutting or removal of the tail extension 61.

60 The fuse element assembly illustrated in Figures 5 and 6 is similar to that shown in Figures 2, 3 and 4, and like or similar parts are indicated by primed reference characters corresponding to the reference characters employed in connection with Figures 2, 3 and 4. This element, however, has looped terminals 65 and 66 made from stranded conducting cable. The loop 65 is adapted to hook over a button 67 on the terminal 68 (Figure 8), which terminal 68 is adapted to be 70 connected to the braided conductor 30 and to the lower end of the spring 27 in the manner of the terminal 32 of the embodiment shown in Figure 1. As before, after setting the device and pulling the extending loop 66 down around the lower end 75

of the casing 5, the loop 79 in the looped extension 66 is adapted to hook over a button 71 on the lower contact ferrule 72 as shown in Figure 7. The laterally extending arms and contact wires 5 of this ferrule correspond with those described in connection with the upper ferrule of Figure 1, and are designated by primed reference characters corresponding with the reference characters in Figure 1.

10 A looped extension 74 of soft copper wire or other suitable material is secured at 75 to the looped terminal 66, and this tail extension is adapted to be grasped for purposes of setting the fuse in the manner of the preceding embodiment, 15 and may be removed at 75 after the fuse is set. With the spring 27 in retracted position, this tail extension extends down from the casing into position to be conveniently grasped.

The inner surface of the button 71 is inclined 20 or tapered at 76, and the inner surface of the button 67 is inclined or tapered at 77. These inclined surfaces give the spaces 78 and 79 wedge-like formation so that proper contact of the cable loop 65 with the button 67 and proper contact of 25 the cable loop 70 with the button 71 is obtained by virtue of the wedging action of the cable loops 65 and 70 in the spaces 78 and 79 and with the wedging or inclined surfaces 76 and 77 of the respective buttons. The spring tension on the element by the spring corresponding with the spring 27, Figure 1, causes the cable loops to wedge under 30 the buttons.

As before, the opposite ends of the cork 52' and tube 54', which is of water-proofed or gummed 35 paper, fiber, or the like, fit over the terminals 80 and 81 of the fuse element assembly and over the adjacent ends of the looped terminals 65 and 66, and the opposite ends of the cork 52' are compressed tightly upon these terminals and upon 40 the adjacent ends of the looped terminals 65 and 66 with the result that the terminals 80 and 81 are bound rigidly together, and the fuse element and strain wire are held rigidly between the parts connected thereby and against free movement between such parts. Crimping or twisting 45 of the fuse element is avoided and, as before, the fuse element assembly constituting a rigid unit, with the difficulty of obtaining the desired original accuracy of the time current blowing characteristics, and the difficulty of maintaining the 50 desired original accuracy of the time current blowing characteristics because of movement of the fuse link and strain wire between the parts connected being thereby avoided. The fuse wire 51' is of silver or other material, the oxide of which is a conductor, and is combined with a "Chromel" or other suitable strain wire 50', and both are completely enclosed and shielded from 55 atmosphere, gases and moisture, and the avoidance of flaking off, deterioration and reducing of the fuse element in cross-section where it is of a material, the oxide of which is non-conducting, are also all avoided. The cork 52 or 52' which is held within the fiber or wrapper paper tube 54 or 54' has an important utility upon blowing 60 of the fuse in the formation of an arc. The cork when subjected to the action of the arc readily evolves by destructive distillation a large amount of gas which assists in extinguishing the arc. 65 This evolution of gas from organic matter, particularly vegetable matter by the heat of the arc, is now well recognized as a highly beneficial action in fuses of the air expulsion type, and my invention provides means for advantageously employing such action.

The fuse shown in Figures 9 to 14 inclusive 5 comprises a casing 85 in the form of a cylindrical tube formed of insulating material similar to that described in connection with Figure 1. The ferrule 86, of cast bronze or other suitable or preferred material, fits over the upper end of the tube 85 and is rigidly secured thereto in any suitable or preferred manner. The ferrule 86 preferably has a round cylindrical outer surface or it may be slabbed along diametrically opposite sides or it may be provided with spring contact means, similar to the spring contact of Figure 1, for cooperation with the upper contact clip (not shown). The upper end of the tube 85 may be reduced to seat the lower end of the ferrule 86 15 at 87.

The upper end of the ferrule 86 is threaded internally as indicated at 88 to receive a cap screw 90. This cap screw 90 has a hexagonal head 91 to facilitate threading the same upon and from the upper end of the ferrule. An upwardly extending axial stud 92 integral with the cap screw 90 is adapted for engagement with a suitable handle (not shown). The cap screw 90 closes the top of the tube 85 and its threaded engagement with the ferrule 86 provides simple and efficient means for establishing both mechanical and electrical connection between the ferrule and the screw. The cap screw 90 also has an integral axial boss 94 extending into the 30 tube 85. The boss 94 has a helical groove 95 for receiving the upper end of the spring 96 by threaded engagement therewith.

The boss 94 has, at its lower end, a socketed 35 part 98 in which the upper end of a flexible braided conductor 100 is rigidly secured. This braided conductor 100 is made of copper or the like and its lower end is connected with the lower terminal member 102 by rigidly securing it in the socketed part 103 thereof. The lower terminal 40 102 has a helical groove 104 for threaded engagement with the lower end of the spring 96. The lower end of the terminal 102 has an integral axial threaded stud 105 which is threaded into a threaded socket 106 in the upper end of the 45 upper terminal 107 of the fuse element assembly. The upper end of this terminal 107 has an outwardly extending annular flange 108 upon which the lower end of the terminal 102 seats when the stud 105 is threaded into place in the socket 106. 50

The fuse element assembly comprises the upper terminal 107, which is formed preferably of copper or other suitable or preferred material, and the lower fuse element assembly terminal 110, formed of similar material. The terminals 107 and 110 of the fuse element assembly are connected by a strain wire or tensile element 112 arranged to bear the mechanical strength. The upper end of this wire 112 is inserted in an axial opening 113 in the terminal 107 and is secured rigidly in place by punching at 114 the stock of the terminal 107 at the inner ends of the openings 115 into firm binding engagement with the wire 112. The lower end of the wire 112 is inserted in an axial opening 116 in the terminal 110 and is secured rigidly in place by punching at 118 the stock of the terminal 110 at the inner ends of the openings 118 into firm binding engagement with the wire 112.

The fuse wire 120 preferably is of pure silver, 70 and the strain wire 112 preferably is of "Chromel" A wire. The upper end of the fuse wire 120 is inserted in an opening 121 in the terminal 107 and is secured firmly in place therein by punching at 122 the adjacent side of the terminal 107 into 75

firm engagement therewith. The lower end of the wire 120 is inserted in an opening 123 in the terminal 110 and is secured firmly in place therein by punching at 124 the adjacent sides of the terminal 110 into firm engagement therewith. Intermediate its ends, the fuse wire 120 is coiled at 125 about the strain wire 112 and a refractory insulating tube 128 formed of glass or other suitable refractory insulating material, such as mica 10 or the like, fits around the strain wire 112 and within the coiled part of the fuse wire 120 to prevent contact between the fuse wire and the strain wire and to shield and isolate each from the other. The opposite ends of the tube 128 15 abut the adjacent ends of the terminals 107 and 110. As in the previous embodiment, while the fuse wire 120 is preferably of silver, as already described, it is to be understood that this wire or fuse element may be of any other suitable 20 fusible conducting material whose oxide is a conductor. The fuse element assembly terminals are preferably of copper or other suitable materials.

The fuse element 120 of silver, or other fusible 25 conducting material whose oxide is a conductor, and the comparatively high resistance strain wire 112, both, are completely enclosed and shielded from atmosphere, gases and moisture, by a tube 135 of fiber or other insulating material, a surrounding cork 136 and an outer enclosing tube 138 of water-proofed paper, gummed paper or the like. The opposite ends of the tube 135 fit telescopically over the reduced ends 139 and 140 of the terminals 107 and 110 of the fuse 30 element assembly. This tube 135 offers no impairment to free separation of the terminals 107 and 110 upon blowing of the fuse, yet, at the same time, it is rigid throughout its length and has abutting engagement at its opposite ends 35 with the shoulders 142 and 143 on the terminals 107 and 110 which, with its fit over the reduced terminal ends 139 and 140, holds the terminals 107 and 110 rigidly together and against relative lateral movement such as otherwise might result in movement or even crimping or twisting of 40 the fuse wire 120 and/or strain wire 112.

As shown in Figure 15, the cork member 136 is made up of two half round corks having complementary depressions 150 adapted to receive 45 and conforming to the outer periphery of the tube 135 and the outer peripheries of the adjacent ends of the terminal members 107 and 110. The opposite ends of the sections of the cork member 136 extend lengthwise sufficiently 50 to embrace and fit over the adjacent ends of the terminal members 107 and 110, and the two cork sections are held together and compressed relatively tightly about the tube 135 and terminals 107 and 110 by forcing them into and enclosing them in the relatively thin tube 138 which, as already pointed out, may be of fiber, or may be a tube rolled from gum paper, or a cover wrapped tightly about the cork member 136. The tube 135 with the cork member 136 and the outer relatively thin enclosing tube 138 completely encloses and shields the fuse element assembly 55 from atmosphere, gases and moisture, and holds the fuse element assembly rigid and against free lateral movement between the parts.

For the purpose of setting the fuse and holding the same set, the lower end of the terminal member 110 is provided with an extension 160 60 formed of stranded conducting cable or other suitable material, three strands of "Depth" cable 65 being employed in the illustrated embodiment,

although this may, of course, vary widely. The stranded cable 160 is looped through an eye 162 in the lower end of the terminal 110 and is twisted at 163 about the integral lower portion 164 of the terminal 110. After the cable is looped through the eye 162, a wedge pin 165 is driven into the eye to bind the cable tightly in place. The opposite ends may be soldered at 166. The lower free ends of the stranded cable 160 are spliced together by a short copper sleeve 10 or ring 168 placed about the same and flattened tightly thereon. Within its length, the stranded conductor 160 is provided with a conical bushing 170 for cooperation with a clip 172 to hold the fuse in set position.

The bushing 170 has an axial passage 173 fitting and soldered, or otherwise rigidly secured, upon the cable 160. A wedge pin 173' may be inserted or driven as a core between the strands of the cable 160 and into the opening 173 to bind additionally the bushing 170 in place on the cable. The clip 172 is secured to the lower end of the integral tongue 174 depending from the lower ferrule 175, which lower ferrule may be of cast bronze or other suitable material and fits over the lower end of the tube 85 and is rigidly secured thereto. The means for securing the clip 172 to the tongue 174 may be in the form of a screw 178 passing through the tongue 174 and threaded into the back of the clip with the back of the tongue 174 recessed or countersunk at 179 to receive the head of the screw 178. The hooked sides 180 of the clip 172 define a vertical eye 181 provided with a front opening 182 and tapered at the bottom at 183 to guide the conical bushing 170 into place. The lower end of the casing 85 is reduced for shouldered engagement with the upper end of the ferrule 175 at 186, and the lower end of the ferrule 175 is flanged inwardly at 187 for cooperation with the lower end of the casing 85. The extension or stranded cable 160 may be flattened at 188 to facilitate passing the same through the front opening 182 between the hooked sides 180 of the clip 172.

The extension or stranded cable 160 constitutes a tail extension which, when the spring 86 is retracted, extends down below the lower end of the fuse casing 85 so that it may be gripped conveniently for setting the fuse and placing the spring 27 under tension. With the spring 86 retracted the setting of the fuse is accomplished by grasping the tail extension 160 and pulling the same downwardly against the tension of the spring 86 until the conical bushing is positioned below or clear of the bottom of the clip 172. The cable 160, above the bushing 170, and particularly the flattened portion 188, is then passed through the opening 182 between the hooked sides of the clip 172. Then upon releasing the tail extension 160, the spring 86 holds the conical bushing 170 up firmly against the hooked sides of the clip 172, and this cooperation of the bushing 170 with these hooked sides of the clip holds the spring 86 extended and the fuse in set position. A circuit is thus established from the ferrule 86, cap screw 90, stranded conductor 160, terminals 103 and 107, fuse link and strain wire assembly 120 and 112, terminal 110, stranded conductor 160, bushing 170 and clip 172, to the lower ferrule 175. The tail extension 160 below the conical bushing 170 may be cut off or otherwise removed after the fuse is set, as above described, but it is to be understood that this removal of a part or all of the tail extension for 75

setting the fuse or anchoring the lower end of the fuse element assembly to the lower terminal on the fuse casing is not necessary within the scope of my present invention.

The longitudinal sectional showing of Figure 17 is on a reduced scale and more or less diagrammatic to show in a single view the device illustrated in Figures 9, 10 and 11. This shows the use of the fuse element assembly in a spring type expulsion fuse. The reference characters are the same as in Figures 9 through 16. One end of the fuse element assembly is detachably secured to the spring system of the fuse. The flexible tail extension is adapted for setting the fuse, and the collar or abutment means thereon anchors the other end of the fuse element assembly. In this type of fuse the cork enclosure 136 closes up the tube 85 toward its open end and increases the expulsive effect.

The fuse shown in Figures 18, 19 and 20, is an ordinary air type expulsion fuse, the particular tube and ferrule arrangement being of the General Electric type. The insulating tube 200 has the metal ferrule 201 threaded upon its upper end. The ferrule 201 has the square part 202 and the reduced tubular extension 203, the lower part of the cylindrical outer surface of which is threaded at 204 for threaded engagement with a metal cap 205 which closes the top of the tube 200. The top of the cap 205 is closed at 206 and the cylindrical outer surface of the cap is knurled or roughened at 207. At diametrically opposite sides of the inner periphery of the tubular extension 203 are longitudinal grooves 208 which open into the bore and extend down from the top of the extension 203.

The lower metal ferrule 210 is secured upon the tube 200 by a screw 211. This ferrule 210 has the cylindrical part 212 at the top of which is the part 213 with the square outer surface and at the bottom of which is the threaded part 214. Integral with the ferrule 210 and depending below the threaded part 214 is an extension 215, the outer surface of which is of conical form and knurled or roughened at 216. The threaded part 214 has notches 217 opening longitudinally therethrough at diametrically opposite sides, and a clamping ring 218 threaded removably upon the threaded part 214 has the knurled or roughened periphery 219 and the reduced extension 220, the bore 221 of which is of conical form conforming generally with but somewhat larger than the knurled conical part 215 of the ferrule 210.

The fuse element assembly in this case is the same as the fuse element assembly of the embodiment of Figures 9 through 17 except that the surrounding enclosure consisting of the cork enclosure 136 and the surrounding tube 186 is slipped off the element assembly. The reference characters applied to the various parts of this assembly are the same as in the embodiment of Figures 9 through 17. With the cap 205 removed, this assembly is introduced through the top of the upper ferrule 201 into the position shown in Figure 18. The flange 108 of the upper fuse link terminal 107 seats upon the top of the reduced extension 204 and anchors the upper end of the element assembly to the ferrule 201. The cap 205, when threaded into place, engages the flange 108 and clamps it upon the end of the extension 203. The flexible tail extension 160 extends down from the lower open end of the tube 200 and is folded or bent up around the lower end of the tube and laid upon the knurled conical periphery 216 of the extension 215 and in one of

the notches 217. The sleeve or ring 168 may be removed from the tail extension 160 if desired. The ring 218 is then telescoped or passed up over the lower end of the tube 200 and is threaded into place upon the lower ferrule as shown. As it is threaded upwardly into place its conical bore 221 engages and effectively clamps the tail extension 160 upon the knurled conical periphery 216 of the extension 215. The cooperation of the conical bore 221 with the knurled surface 216 has a clamping action of wedge-like character upon the tail extension 160 to anchor the same securely to the lower terminal. In this case, the generally conical bushing 170 on the tail extension 160 acts as a plug within the tube 200 tending to close the tube to increase the expulsive effect. This assists in the expulsion of the flexible cable where the fuse element assembly is used in this type of fuse. It is apparent, of course, that in this type of fuse there is no spring system within the fuse, and the upper terminal 107 of the fuse link assembly, instead of being connected to the spring system as in the previous embodiment, serves to anchor directly the upper end of the element assembly.

The present invention is capable of a wide range of modifications and is adapted for a wide range of uses, and I do not intend, therefore, to be limited to the particular details nor to the particular use or manner of use shown or described.

I claim:

1. In an air expulsion fuse, an enclosed fuse element assembly having a fuse element, a strain wire in parallel with the fuse element and a rigid sleeve of insulation out of contact with the fuse element to prevent flexing of the fuse element.
2. In an air expulsion fuse, a silver fuse link, a comparatively high resistance strain element, and means enclosing and covering both said fuse link and said strain element against contaminating and corrosive agents, said means also preventing bending of said element and said link and being out of contact with the same.
3. In an air expulsion fuse, a fuse link assembly comprising a pair of fuse link terminals, a silver fuse link and a comparatively high resistance strain element connected between said terminals, and a rigid insulating tube surrounding and enclosing said fuse link and said strain element and cooperating with said fuse link terminals to hold same rigidly in position and limiting the access of atmospheric gases to said link.
4. In a fuse link assembly, a pair of fuse link terminals between which an arc is adapted to be drawn, a fuse link connected between said terminals, a strain element connected between said terminals, a fibrous insulating tube surrounding and enclosing said fuse link and said strain element and cooperating with the fuse link terminals to hold same rigidly in position, means within said tube for insulating the fuse link from the strain element, a light insulating enclosure surrounding and enclosing said tube and the adjacent ends of the fuse link terminals, and a covering enclosing said last enclosure.
5. In a fuse link assembly a pair of fuse link terminals between which an arc is adapted to be drawn, a fuse link connected between said terminals, a strain element connected between said terminals, an insulating tube surrounding and enclosing said fuse link and said strain element and cooperating with said fuse link terminals to hold same rigidly in position, and insulating

- means within said tube for separating the fuse link from said strain element.
6. In a fuse link assembly a pair of fuse link terminals between which an arc is adapted to be drawn, a fuse link connected between said terminals, a strain element connected between said terminals, an insulating tube surrounding and enclosing said fuse link and said strain element and cooperating with said fuse link terminals to hold same rigidly in position, insulating means within said tube for separating the fuse link from said strain element, and a tail extension on one of said fuse link terminals and a contact terminal carried on said tail extension intermediate its end.
7. In a fuse link assembly a pair of fuse link terminals between which an arc is adapted to be drawn, a fuse link connected between said terminals, a strain element connected between said terminals, an insulating tube surrounding and enclosing said fuse link and said strain element and cooperating with said fuse link terminals to hold same rigidly in position, insulating means within said tube for separating the fuse link from said strain element, a tail extension on one of said fuse link terminals, said tail extension comprising a stranded conductor, and anchoring means on said stranded conductor for anchoring said tail extension to an electrical terminal.
8. In a fuse device, a fiber tube, a fusible link within said tube, a cork enclosure surrounding said tube, and a relatively thin paper cover enclosing said cork enclosure.
9. In a fuse device, a fiber tube, a fusible link within said tube, a sectionalized cork enclosure surrounding said tube, and a relatively thin paper cover surrounding said cork enclosure and holding the cork enclosure compressed and the sections thereof together.
10. In a fuse device, a fiber tube, a strain element within said tube, a refractory insulating sleeve surrounding said strain element, a fusible link disposed within said tube and coiled about said sleeve, a cork enclosure surrounding said tube and a relatively thin paper cover enclosing said cork enclosure.
11. In a fuse device, a pair of fuse terminals between which an arc is adapted to be formed, a fusible link connected between said terminals, a strain element connected between said terminals, a fiber tube surrounding and enclosing said fusible link and said strain element and telescopically engaged at opposite ends with said terminals, means within said tube for insulating said fusible link from said strain element, a cork enclosure surrounding said tube and fitting at opposite ends over said terminals, and a thin insulating tube enclosing said cork enclosure.
12. In combination, a tubular casing, an upper terminal on said casing, a lower terminal on said casing, a fuse link assembly adapted for disposition within said casing and comprising an upper terminal adapted to be anchored to the upper terminal on the casing and a lower terminal, a fusible link connected between the terminals of said fuse link assembly, a strain element connected between the terminals of said fuse link assembly, an insulating sleeve surrounding and enclosing said fusible link and said strain element and cooperating with the terminals of the fuse link assembly to hold the same rigidly in position, and a tail extension on the lower terminal of the fuse link assembly and extending down through and bent around the bottom of the cas-
- ing and fastened to the lower terminal on the casing.
13. In combination, a tubular casing, an upper terminal on said casing, a lower terminal on said casing, a fuse link assembly adapted for disposition within said casing and comprising an upper terminal adapted to be anchored to the upper terminal on the casing and a lower terminal, a fusible link connected between the terminals of said fuse link assembly, a strain element connected between the terminals of said fuse link assembly, an insulating sleeve surrounding and enclosing said fusible link and said strain element and cooperating with the terminals of the fuse link assembly to hold the same rigidly in position, and a tail extension extending from the lower terminal of the fuse link assembly and adapted to be fastened to the lower terminal on the casing.
14. In combination, a tubular casing, an upper terminal on said casing, a lower terminal on said casing, a fuse link assembly adapted for disposition within said casing and adapted to be anchored at its upper end to the upper terminal on the casing, a clip on the lower terminal on the fuse link assembly and adapted to be placed in said clip, and an anchoring element on said tail extension and adapted to cooperate with said clip to anchor said extension to the lower terminal on the casing when said extension is placed in said clip.
15. In combination, a tubular casing, an upper terminal on said casing, a lower terminal on said casing, a fuse link assembly adapted for disposition within said casing and comprising an upper terminal adapted to be anchored to the upper terminal on the casing and a lower terminal, a fusible link connected between the terminals of said fuse link assembly, a strain element connected between the terminals of the fuse link assembly, a fibrous insulating tube surrounding and enclosing said fusible link and said strain element, refractory insulating material disposed within said tube and insulating the fusible link from the strain element, a light porous insulating enclosure surrounding and enclosing said tube and the adjacent ends of the terminals of the fuse link assembly, an outer insulating tube surrounding said last enclosure, and a tail extension extending from the lower terminal of the fuse link assembly and adapted to be fastened to the lower terminal on the casing.
16. In combination, a tubular casing, an upper terminal on said casing, a lower terminal on said casing, a fuse link assembly adapted for disposition within said casing and comprising an upper terminal adapted to be anchored to the upper terminal on the casing and a lower terminal, a fusible link connected between the terminals of the fuse link assembly and formed of material whose oxide is a conductor, a relatively high resistance strain element connected between the terminals of the fuse link assembly, a fibrous insulating tube surrounding and enclosing said fusible link and said strain element and cooperating with the terminals of the fuse link assembly to hold the same rigidly in position, a refractory insulating sleeve surrounding said strain element and insulating it from the fusible link, a cork enclosure surrounding and enclosing said fibrous insulating tube and the adjacent ends of the terminals of the fuse link assembly, a paper covering surrounding and enclosing said cork enclosure, and a tail extension extending from the lower terminal of the fuse link assembly and

adapted to be fastened to the lower terminal on the casing.

17. A fuse element comprising a strain element in the form of a closed loop, a fuse element folded and disposed within said loop, and an insulating enclosure around the fuse element and interposed between it and the strain element.

18. A fuse element comprising a strain element in the form of a closed loop, a fuse element folded and disposed within said loop, an insulating enclosure around the fuse element and interposed between it and the strain element, an apertured conducting tube surrounding one end of the strain element and the adjacent end of the fuse element and flattened thereon, a conducting tube surrounding the other end of the strain element and the adjacent end of the fuse element and flattened thereon, and a conducting extension on said last tube.

19. A fuse element comprising a strain element in the form of a closed loop, a fuse element folded and disposed within said loop, an insulating enclosure around the fuse element and interposed between it and the strain element, a pair of half round corks surrounding said fuse and strain element and a water-proofed paper tubing around said corks.

20. A fuse element comprising a strain element in the form of a closed loop, a fuse element disposed within said loop, an insulating enclosure around the fuse element and interposed between it and the strain element, a cork enclosure around said strain and fuse elements, a water-proofed paper tubing surrounding said cork element, and looped terminals formed of stranded cable and extending from the opposite ends of the said fuse and strain elements.

21. In combination, a fuse element assembly consisting of a silver fuse wire paralleled by a nickel chromium alloy strain wire, a rigid enclosure surrounding said wires and a secondary enclosure surrounding said first enclosure for use with said assembly in one type of expulsion fuse, said secondary enclosure being adapted to be slipped off said element assembly for use of said assembly in another type of fuse.

22. In combination, a pair of fuse link terminals between which an arc is adapted to be drawn, a fuse link connected between said terminals, a strain element connected between said terminals, an insulating enclosure surrounding said fuse link and said strain element, a flexible stranded wire tail extension on one of said fuse link terminals, and means on the other fuse link terminal for anchoring one end of said fuse link assembly and means for holding said stranded wire extension, said means having a wedging contact engagement energized by tension on the stranded wire.

23. In combination, a pair of fuse link terminals between which an arc is adapted to be drawn, a fuse link connected between said terminals, a strain element connected between said terminals, an insulating enclosure surrounding said fuse link and said strain element, a flexible tail extension on one of said fuse link terminals, and an abutment on said flexible tail extension.

24. In combination, a pair of fuse link terminals between which an arc is adapted to be drawn, a fuse link connected between said terminals, a strain element connected between said terminals, an insulating enclosure surrounding said fuse link and said strain element, and a flanged head on one of said fuse link terminals for anchoring one end of said fuse link assembly in an ordinary air expulsion fuse, said head having an axial socket

threaded for detachable connection to the spring system of a spring type expulsion fuse.

25. In combination, a fuse link comprising leads ending in rigid terminals, a rigid insulating envelope joining said terminals mechanically, and a fusible link within said envelope and being out of contact with said envelope at least one of said terminals being freely retractile from said envelope upon melting of said fusible link.

26. In combination, a fuse link comprising leads ending in rigid terminals, a rigid insulating envelope joining said terminals mechanically, a fusible link within said envelope and being out of contact with said envelope, and a heat insulating envelope embracing said terminals and said envelope at least one of said terminals being freely retractile from said envelope upon melting of said fusible link.

27. In a fuse of the class described, terminal members, a fuse wire connected between said members, and an air excluding sleeve of relatively small air containing capacity enclosing said fuse but lying out of contact with the same and having its ends substantially closed by said terminals at least one of said terminal members being freely retractile from said sleeve upon melting of said fuse.

28. In a fuse of the class described, a pair of terminals, a tension sustaining connection between said terminals and adapted to resist separation of said terminals, a fusible link of greater length than the distance between said terminals for connecting said terminals electrically, said connection and said link being out of contact with each other, and a stiff insulating sleeve of small internal diameter enclosing said link and connecting element and forming a strut endwise between said terminals.

29. In a fuse of the class described, a pair of substantially rigid terminals having each a pair of longitudinal bores extending from their end faces, a strain wire having its ends disposed in and gripped by one of the bores of each terminal, a fusible wire having its ends disposed in and gripped by the other of the bores of each terminal, and a rigid tube of insulation embracing the ends of the terminals.

30. In a fuse device, the combination of a pair of terminals, a fiber tube having its ends resting on and closed by said terminals, a strain element within said tube connecting the terminals, an insulating sleeve surrounding said strain element, and a fusible link disposed within said tube and coiled about said sleeve, said link having its ends connected to said terminals.

31. In combination, a pair of aligned cylindrical terminals, an outer sleeve of fibrous insulation aligned with said terminals and having its ends substantially closed by said terminals, an inner sleeve of vitreous insulation also aligned with said terminals and disposed between them, said sleeves defining two concentric chambers, tension sustaining means enclosed in one of said chambers and connecting said terminals, and a fusible link enclosed in the other of said chambers connecting said terminals.

32. In combination, a pair of aligned cylindrical terminals one of which has a flange for mounting in an annular stationary terminal, the other of which has a flexible stranded lead for attachment to another stationary terminal, a pair of concentric sleeves of insulation disposed in axial alignment between the ends of said terminals, a strain wire within one of the sleeves, and a fuse wire within the other of said sleeves,

one of said sleeves and strain wire holding said terminals in spaced alignment.

33. In a fuse of the class described, a fuse sleeve having permanent terminals for the attachment of a replaceable fuse link, a spring for tensioning the link, a replaceable fuse link comprising two terminal portions connected by a fusible conductor and a flexible stranded wire conductor in series, one of said permanent terminals and said last mentioned terminal portion having self-tightening wedging engagement under the action of the spring.

34. In a fuse of the class described, a fuse sleeve having permanent terminals for the attachment of a replaceable fuse link, a spring for tensioning the link, a replaceable fuse link comprising two terminal portions connected by a fusible conductor and a flexible stranded wire conductor in series, said flexible stranded conductor having a portion extending beyond the adjacent terminal portion, one of said permanent terminals and said last mentioned terminal portion having self-tightening wedging engagement under the action of the spring.

25 35. In combination, a sleeve, a fusible link in the sleeve, a spring in the sleeve for tensioning the link, said link comprising a fusible portion and a flexible stranded wire lead provided with a contact portion, and said sleeve having a stationary terminal engageable with the contact portion of said lead to provide a wedging contact engagement which is self-tightening under the action of said spring.

36. In combination, a fuse sleeve having permanent terminals for a renewable fuse link, a renewable link comprising a fusible portion and a flexible stranded lead provided with a terminal portion, a spring for tensioning said link, said terminal portion and one of said permanent terminals having a wedging engagement providing electrical contact which is improved by the action of the spring.

37. In combination, a fuse sleeve having a permanent terminal which is movable, a permanent hooked terminal which is stationary, a spring for the movable terminal, and a fuse link having a fusible portion and a pliant loop for hooking over and being tensioned by said spring upon said hooked terminal said hooked terminal providing a V-shaped wedging portion for receiving said pliant loop.

38. In combination, a fuse sleeve having a permanent button-like terminal which is movable, a permanent button-like terminal which is stationary, a spring for said movable terminal, and a fuse link having a fusible portion and looped pliant ends for buttoning upon said button-like terminals, said spring holding said pliant loops in good contact with said terminals.

60 39. A fuse link comprising a fusible portion including a fusible wire and a strain wire for relieving the fusible wire of tension and pliant stranded wire loops forming terminals for said fusible portion.

65 40. In a fuse link, a pair of terminals, a silver fuse wire, connecting said terminals, a small tubular enclosure for the silver fuse wire for shielding it from atmosphere, said enclosure being capable of withstanding a relatively high temperature and being out of contact with said wire and a high tensile strength connection for resisting tension between said terminals, said connection being symmetrically disposed to avoid cocking of the terminals.

75 41. A refill for an expulsion fuse comprising a

strain wire adapted to stand normally under spring tension, a fuse wire, a surrounding tubular insulating member, and means to prevent the fuse wire from contacting the strain wire or insulating member.

5 42. A refill for an expulsion fuse, a pair of terminals, a metallic tension resisting member constituting an electrical connection between said terminals adapted to stand normally under tension, and a compression resisting member of insulation surrounding the tension resisting member and being disposed in engagement with at least one of the terminals, the other of said pair of terminals being capable of withdrawal freely from said member of insulation upon melting of the tension resisting element.

10 43. In a fuse link for an air expulsion type fuse a pair of terminals, a sleeve of insulation supported on and surrounding the terminals, a fusible link connecting the terminals, and means between the link and the sleeve to protect said sleeve from injury by the heat of the link at least one of said pair of terminals being capable of withdrawal freely from said sleeve upon melting of the fusible link.

15 44. In a fuse link for an air expulsion type fuse, a pair of substantially cylindrical terminals, a rigid tubular sleeve of insulation telescopically supported on and centered by at least one of said terminals, a strain wire and a link connecting said terminals and being disposed in concentric relation out of contact with each other within the sleeve.

20 45. In a fuse link for an air expulsion type fuse, a pair of terminals, a fuse link, and a strain wire disposed out of contact with each other, a tubular sleeve supported telescopically with at least one of said terminals and being out of contact with the fuse link, means for connecting one terminal to a cooperating conductor, and a flexible lead extending from the other terminal.

25 46. In a fuse link for an air expulsion type fuse, a pair of terminals, a fuse link, and a strain wire disposed out of contact with each other, a tubular sleeve supported telescopically with at least one of said terminals and being out of contact with the fuse link, means for connecting one terminal to a cooperating conductor, a flexible lead extending from the other terminal, and spring means for tensioning the strain wire.

30 47. In a fuse link for an air expulsion type fuse, a pair of terminals, a fuse link, and a strain wire disposed out of contact with each other, a tubular sleeve supported telescopically with at least one of said terminals, means for connecting one terminal to a cooperating conductor, and a flexible lead extending from the other terminal, said connecting means having a longitudinally threaded end portion.

35 48. In an air expulsion fuse, an enclosed fuse element assembly having a fuse element, a protective sleeve of insulation to limit the access of atmospheric gases, and means between said element and said sleeve to protect said sleeve of insulation from deterioration.

40 49. In an air expulsion fuse, an enclosed fuse element assembly having a silver fuse element and a high tensile strength strain wire, a surrounding tubular sleeve of insulation, and means between said element and said sleeve to protect said sleeve of insulation from deterioration by the heat of the element at its working temperature.

45 50. In an air expulsion fuse, a pair of terminals, a fusible link connecting said terminals, a

high tensile strength mechanical link connected between said terminals, a sleeve of insulation maintained in alignment on said terminals surrounding the fusible link and said mechanical link, and insulating means between said links and disposed inside said sleeve.

51. In an air expulsion fuse, a pair of terminals, a fusible link connecting said terminals, a strain link connecting said terminals, and a rigid sleeve of insulation centered on said terminals to hold the terminals substantially in alignment and to prevent injury to said links.

52. In a fuse device, the combination of a tube of insulation adapted to be closed at one end, a terminal member at said end, the other end of the tube permitting the escape of gases when the fusible portion blows, a conductor extending through the tube, one end of the conductor being joined to the terminal member, said conductor having a pair of substantially rigid infusible terminals joined by a fusible portion comprising a fusible element and a tension element in parallel between said infusible terminals, said fusible portion being disposed within the tube and adapted to be melted upon excessive current flow through the conductor, said tension element being adapted to stand normally under spring tension, and a spring connected to the conductor at one side of the fusible portion for extending the gap made by fusing of the fusible portion, the reaction of the spring being supported on said first named terminal member and upon the second end of the tube, said conductor having a flexible stranded wire portion extending outside the tube for connection with a second terminal remote from the second end.

53. In a fuse device, the combination of a tube of insulation adapted to be closed at one end, a terminal member at said end, the other end of the tube permitting the escape of gases when the fusible portion blows, a conductor extending through the tube, one end of the conductor being joined to the terminal member, said conductor having a pair of substantially rigid infusible terminals joined by a fusible portion comprising a fusible element and a tension element in parallel between said infusible terminals, said fusible portion being disposed within the tube and adapted to be melted upon excessive current flow through the conductor, said tension element being adapted to stand normally under spring tension, a spring connected to the conductor at one side of the fusible portion for extending the gap made by fusing of the fusible portion, the reaction of the spring being supported on said first named terminal member and upon the second end of the tube, said conductor having a flexible stranded wire portion extending outside the tube for connection with a second terminal remote from the second end, and a tubular organic insulating sleeve embracing but being out of contact with the fusible element.

54. In a fuse device, the combination of a tube of insulation adapted to be closed at one end, a terminal member at said end, the other end of the tube permitting the escape of gases when the fusible portion blows, a conductor extending through the tube, one end of the conductor being joined to the terminal member, said conductor having a pair of substantially rigid infusible terminals joined by a fusible portion comprising a fusible element and a tension element in parallel between said infusible terminals, said fusible portion being disposed within the

tube and adapted to be melted upon excessive current flow through the conductor, said tension element being adapted to stand normally under spring tension, a spring connected to the conductor at one side of the fusible portion for extending the gap made by fusing of the fusible portion, the reaction of the spring being supported on said first named terminal member and upon the second end of the tube, said conductor having a flexible stranded wire portion extending outside the tube for connection with a second terminal remote from the second end, and a fiber tube closely embracing but being out of contact with the fusible element.

55. In a fuse device, the combination of a tube of insulation adapted to be closed at one end, a terminal member at said end, the other end of the tube permitting the escape of gases when the fusible portion blows, a conductor extending through the tube, one end of the conductor being joined to the terminal member, said conductor having a fusible portion comprising a fusible element and a tension element in parallel disposed within the tube and adapted to be melted upon excessive current flow through the conductor, said tension element being adapted to stand normally under spring tension, a spring connected to the conductor at one side of the fusible portion for extending the gap made by fusing of the fusible portion, the reaction of the spring being supported on said terminal and upon the second end of the tube, a second terminal associated with but spaced from the second end of the tube, said conductor having a flexible stranded wire portion extending outside the tube for connection with said second terminal, and a wedging contact between said second terminal and said flexible wire portion, which wedging contact is improved by the force of the spring.

56. A fuse link comprising a pair of substantially rigid terminals, a fusible conductor and a strain wire secured to and extending between said terminals, insulating means engaging said terminals and holding them substantially in alignment to protect the fusible conductor and strain wire against injury by flexure, said means lying out of contact with said fusible conductor and strain wire.

57. The combination with claim 56 of conductors joined to said terminals for extending the circuit thereof, one of said last named conductors being a flexible lead, the terminal to which said flexible lead is connected being free to separate from said insulating means by motion endwise thereof upon melting of the fusible conductor and said strain wire.

58. A fuse link comprising a pair of substantially rigid terminals, a fusible conductor of relatively high melting point joining said terminals, an insulating sleeve engaging said terminals and holding them substantially in alignment to protect the fusible conductor against injury by flexure, said insulating sleeve comprising insulation of vegetable origin which would tend to be charred by the working temperature of the fusible conductor, said sleeve being out of thermal contact with said fusible conductor and at least one of said terminals being freely movable endwise out of engagement with said sleeve upon melting of said conductor.

59. A self-supporting link comprising a sleeve of organic insulation, rigid terminals extending into the ends of said sleeve, a silver fuse wire connecting said terminals and lying out of con-

tact with said sleeve, and a flexible stranded lead extending from one of said terminals, said one of the terminals being free to be expelled from the sleeve.

5 60. A fuse link comprising a pair of terminals, fusible conducting means connected between said terminals, a tubular insulating sleeve consisting chiefly of material of vegetable origin surrounding the fusible conducting means loosely and telescoping with said terminals, one of said terminals being free to move out of the adjacent end of the sleeve upon melting of the fusible conducting means, and a flexible stranded conductor connected to said one terminal for 15 extending the circuit thereof.

61. In a fuse link having detachable terminal portions, one of which is a flexible stranded lead, a pair of relatively heavy and relatively infusible fuse terminals carried between said detachable 20 terminal portions, a fusible section connecting the fuse terminals, said section comprising a strain element and a fusible element connected in parallel between said fuse terminals and a tubular insulating member surrounding the adjacent 25 ends of the fuse terminals to give the fusible section mechanical support against bending.

62. A fuse link for use as a replacement in a reusable fuse tube comprising the combination of 30 a pair of terminals which are relatively heavy and infusible, the first one of said terminals having a coupling by which the link is supportable in the reusable fuse tube, the second one of said terminals having a flexible lead connected to it 35 and extending therefrom, which flexible lead is adapted to be anchored outside the bore of the reusable fuse tube, said flexible lead permitting the second fuse terminal to be expelled from the reusable fuse tube upon the occurrence of a 40 heavy current arc between the fuse terminals, a fusible element electrically connected between the fuse terminals, a stress sustaining element connecting said fuse terminals whereby in the event that the fuse link is subjected to tension, 45 the fusible element will be relieved of tension, and an insulating pressure resisting tube telescoped with said fuse terminals, said tube trapping sufficient pressure between said fuse terminals upon the blowing of the fusible element 50 and stress sustaining element to produce an expulsion effect upon said second terminal sufficient to drive it out of said pressure resisting tube.

63. The fuse link of claim 62 wherein the 55 pressure resisting tube has means for securing a substantially gas tight seal with at least one of said fuse terminals.

64. A replaceable fuse link for breaking circuit in air comprising cylindrical fuse terminals of 60 relatively large diameter, a stress sustaining wire of small diameter connecting said terminals and disposed substantially coaxially of the terminals, a fusible element of relatively small diameter wire disposed in a helical coil of relatively large diameter 65 substantially coaxially about said stress sustaining wire and connecting said terminals, a flexible lead wire attached at its inner end to one of the fuse terminals and having its opposite end free for making a desired connection at any intermediate point, and a sleeve of insulation carried by said link, said sleeve being telescopically disposed with respect to said fuse ter-

minals and enclosing but lying out of contact with said helically coiled fusible wire.

65. For use with a pair of spring separated mounting terminals, a renewable link comprising a pair of fuse terminals, a fusible element connecting said terminals, a tube of insulation telescoped with said terminals and carried by said link, at least one of said terminals being freely movable out of said tube, said terminals having flexible extensions terminating in anchoring members, and a rigid loop connected to one of said extensions for facilitating the mounting of said link upon said mounting terminals.

66. In a fuse, a pair of fuse terminals, a fusible element connected between said terminals, spring means tending to separate said terminals, a strain element also interconnecting said terminals for relieving said fusible element of the stress imposed by said spring, and a fiber tube surrounding said fusible and strain elements and being telescoped with said terminals and supported upon at least one of them, said tube having a lining of material which upon being exposed to an arc evolves freely a gaseous medium which assists in extinguishing the arc.

67. In a fuse, a pair of fuse terminals, a fusible element connected between said terminals, a tube of waterproofed insulation surrounding said fusible element and being telescoped with said terminals and supported out of contact with said fusible element, the ends of said tube being closed and said tube having a lining of a material which upon being exposed to the arc formed between said terminals on blowing of said fusible element evolves a gaseous medium which assists in extinguishing it.

68. A fuse link comprising a pair of fuse terminals, a fusible element and a strain element interconnecting said terminals, a tube of waterproofed insulation surrounding said fusible and strain elements and said fuse terminals, flexible leads connected to said terminals and extending out of the ends of said tube, said tube being supported out of contact with said fusible and strain elements, and a lining in said tube formed of a material which evolves a gaseous medium on being exposed to the arc formed between said terminals on blowing of said fusible and strain elements for assisting in extinguishing it.

69. A fuse link comprising a pair of terminals 50 having shoulder portions facing each other, a flexible conductor connected to one of said terminals, fusible means interconnecting said terminals, and a fiber tube surrounding said fusible means and spaced therefrom and interfiting with said shoulders.

70. In a fuse link, in combination, a fusible element, a conductor, and a sleeve, one end of said fusible element overlapping one end of said conductor, said sleeve being coextensive with said overlapping ends and deformed thereon to prevent separation thereof by frictional engagement therewith.

71. In a fuse link, in combination, a fusible element, a strain element paralleling said fusible element, a flexible conductor, and a metal sleeve, 65 one end of each of said elements having overlapping engagement with one end of said flexible conductor, said metal sleeve being coextensive with said overlapping ends and arranged and 70 adapted to prevent separation thereof by frictional engagement therewith.

ALLAN RAMSEY.
